LOOKOUT OR DOOR PEEP

Filed Nov. 9, 1928

FIG. 1

FIG. 2

FIG. 3

FIG. 4

FIG. 5

INVENTOR
Harry Sklar
BY
William E. Lee
ATTORNEY

UNITED STATES PATENT OFFICE.

HARRY SKLAR, OF NEW YORK, N. Y.

LOOKOUT OR DOOR-PEEP.

Application filed November 9, 1928. Serial No. 318,154.

This invention relates generally to improvements on door-peeps such as are used for enabling a person desiring admission to be subjected to view, or addressed, without opening the door. More specifically, my invention relates to an arrangement whereby the observer on one side of the door can view the person on the other side without subjecting himself to attack by the person on the other side.

The object of my invention generally is the provision of a new and useful door-peep or lookout which has features not hitherto employed in such an arrangement.

For the attachment of these objects and such other objects as may hereinafter appear or be pointed out, I have illustrated in the drawings an embodiment of my invention, wherein:

Fig. 1 is a front elevational view of a door-peep embodying my invention.

Fig. 2 is an elevational view taken from the rear of Fig. 1.

Fig. 3 is a sectional view taken on the line 3—3 of Fig. 2 showing the peep, open for observation.

Fig. 4 is a sectional view similar to Fig. 3 with the parts in a different relation; and

Fig. 5 is a side elevational view looking at Fig. 2 from the left.

Before proceeding to describe my invention I will premise that the device shown in the drawings is intended to be fixed in position either on or adjacent to a door of a dwelling, a store or the like, and comprises generally a frame 10 having an opening 11 therethrough, illustrated in the drawings as circular, and two superposed closures 12 and 13 for said opening.

The frame 10 can be given any preferred or desired contour or conformation and is secured in position by members (not shown) passed through the openings 15. The frame 10 may be provided with a depressed portion 16 in which will appear the name of the occupant or dweller. Mounted upon the frame 10 and to one side of the circular opening 11 are the upstanding pintles 20 in which is secured the pivot pin 21, and mounted upon this pivot pin 21 for swinging movement thereabout are the pintles 23 carried by the outer door 12 and the pintles 24 carried by the inner door 13. The outer door 12 has been illustrated in the drawing as having a transparent section and the

inner door 13 as opaque, so as to permit the person on the inside to swing the inner door 13 about its pivot and get a view of the person through the transparent door and then, if it is desired to carry on a conversation or to passing something through, to open the inner door also.

The portion of the frame 10 which defines the circular opening 11 comprises generally the upstanding annular ridge 25, the outwardly extending flange 26 and the inwardly extending flange 27. There is thus formed an exterior annular space 28 by means of which the frame can be countersunk in the door, and the interior annular space 29 in which the two closures 12 and 13 can be received.

The outer closure 12 is flanged so as to provide a seat for the transparent crystal 30 which may be locked in position by means of the ring 31. This door 12 is illustrated as free to swing on the pivot pin 21 to open or closed position.

The inner door 13 is biased to its closed position by means of the spiral spring 31', one end 32 of which abuts against the frame 10 and the other end 33 of which abuts the door, the spring being held between the pintles 24.

One of the objects of my invention is the provision of an arrangement by which both doors can be held closed against opening except from the inside and yet which will permit optionally of the opening of either the inner door 13 by itself or of both doors and I will now describe the details of this arrangement.

Fixed to and upstanding from the flange 25 is the latch member 35 having a hooked nose as shown at 36. Carried along the outer edge of the inner door 13 is the coacting latch member 37 carried by the sleeve 38 which is normally spring-pressed outwardly by the spring 39 which has one end abutting against and fixed to the door 13 and the other end 40 in engagement with a portion 34 of the sleeve 38. The sleeve 38 is so constructed and mounted as to permit both a rotating movement as well as a movement thereof toward the closure 13 when it is depressed. The coacting latches 35 and 37 are so positioned that when the door 13 is biased to its closed position under the action of the spring 31', the latch 37 will be cammed over the nose 36 of the latch 35

into locking engagement therewith and this is permitted by the fact that the sleeve 38 is permitted a limited rotative movement.

The outer door 12 has extending upwardly 5 from the upstanding annular flange, a latch 41 undercut as shown at 42, the annular flange 25 of the frame 10 being cut away as shown at 43 in Fig. 2 so as to receive therein the latch 42 which projects outwardly and 10 beyond the frame of the outer door 12. The lower portion of the latch 41 is in a plane closer to the frame 10 than is the lower portion of the nose 36 of the latch 35, as will be 15 observed upon viewing Fig. 5 of the drawings, and the sleeve 38 carrying the latch 37 has an inward movement which not only permits it to engage beneath the hook 36 but also permits the latch 37 to be forced 20 inwardly closer to the frame, and this along with the rotative movement which can be 25 given the sleeve permits the latch 37 to be forced inwardly and moved angularly so as to bring it beneath the nose of the latch 41 on the outer door 12.

With this description it will be understood that, with the parts shown in Figs. 2 and 5 of the drawings, when it is desired to merely open the inner opaque door 13 the sleeve 38 is grasped in the hand and rotated 30 slightly clockwise so as to disengage the lug 37 from beneath the nose 36, and is then swung outwardly about its pivot 21, which will bring the parts to the position shown in Fig. 3 of the drawings. Where, on the other 35 hand, it is desired to open both doors, the sleeve 38 is first forced inwardly toward the frame 10 and then rotated so as to bring the hook 37 into engagement in the undercut portion 42 and beneath the nose of the latch 41, which causes the two doors to move 40 together and that with an outward pull upon the sleeve 38 to swing the door 13 about its pivot, the door 12 will also be swung with it.

It will thus be seen that I have provided 45 an arrangement which permits an inspection of the exterior from the inside room or chamber without exposing the room or those inside the room to the action of dust, dirt or draft from the exterior or to the possibility 50 of something being pushed through or into the opening.

When it is desired to move the closure 13 to open position without moving the outer closure 12, (see Fig. 3), I have found that 55 it is advisable that some means be provided for preventing the opening of the outer closure 12 by pressure from without. These means are shown in Figs. 3 and 4 as comprising a cam extension 45 extending outwardly from the pintles 24, the cams being so arranged that when the door 13 is swung about the pivot pin 21 to open position the cams engage the door 12 and lock the outer closure in closed position. This is clearly 60 shown in Fig. 3 of the drawings.

The outer door or closure 12 has been illustrated in the drawings as free to be moved to open position by pressure brought to bear from the outside thereof. It will be understood, however, that where desired 70 this outer door can have associated therewith any conventional form of means for holding it locked to the frame 10 in such a manner that only by manipulation of these means from the inside can this outer door 75 be moved to open position in the manner already indicated. Such means have not been shown because they can take any conventional forms such as are now in common use for this purpose.

Where devices of the character herein disclosed are to be employed in connection with apartments or the like, in which number or letter designations are employed, as for example "5G", I can associate this number or letter designation with my arrangement herein disclosed so as to have the frame and its associated parts form also the means for designating the apartment. For example, in Figs. 1 and 3 of the drawings, I show this as accomplished by positioning outside of the opaque closure 13 so that it can be seen from the outside, the designation "5G" where my arrangement is to be employed with an apartment so designated. 95 This designation may take the form of an opaque member arranged to be secured to or associated with the inside surface of the transparent crystal 30, this opaque member having the designation "5G" cut there-through so that the cutout portion thereof can serve not only as the apartment designation but also as a peephole of limited size so as to prevent the person from the outside viewing either the person on the inside or the interior of the apartment. This designation, it will be understood, can also take the form of a printed or otherwise formed designation "5G" associated with the outside face of the inner closure 13.

Having thus described my invention and illustrated its use, what I claim as new and desire to secure by Letters Patent is:

1. A device of the character described, comprising a frame adapted to be associated with an opening through a door or the like, an opening through said frame, a plurality of closures for said last mentioned opening, the outer of said closures having a transparent portion and the inner closure being opaque, whereby upon opening the inner closure a view can be had through the frame, said closures being mounted upon a common pivot, and releasable locking means for securing said inner closure locked upon the frame, said releasable locking means being movable into engagement with the outer closure to cause the two to move as a unit.

2. A device of the character described comprising a frame adapted to be associated

with an opening through a door or the like, an opening through said frame, a plurality of closures for said last mentioned opening, the outer of said closures having a transparent portion and the inner closure being opaque, whereby upon opening the inner closure a view can be had through the frame, said closures being mounted upon a common pivot, and releasable locking means for securing said inner closure locked upon the frame, said releasable locking means being movable in one direction to lock the inner closure to the frame and in another direction to lock the inner closure to the outer closure.

3. A device of the character described, comprising a frame adapted to be associated with an opening through a door or the like, an opening through said frame, a plurality of closures for said last mentioned opening, the outer of said closures having a transparent portion, both closures being mounted for swinging movement to and from their closed position, engaging means on the frame and other engaging means on the outer closure, and means carried by the inner closure to engage alternatively with either of said means so as to engage the inner closure with the frame to lock said closures, or to release said inner closure

from the frame and engage it with the outer closure so as to permit both closures to be opened as a unit.

4. A device of the character described, comprising a frame adapted to be associated with an opening through a door or the like, an opening through said frame, a plurality of closures for said last mentioned opening, the outer of said closures having a transparent portion, both closures being mounted for swinging movement to and from their closed position, engaging means on the frame and other engaging means on the outer closure, and means carried by the inner closure to engage alternatively with either of said means so as to engage the inner closure with the frame to lock said closure, or to release said inner closure from the frame and engage it with the outer closure so as to permit both closures to be opened as a unit, and means automatically operative when the inner closure is moved to open position free of engagement with the outer closure, for maintaining said outer closure down upon the frame.

In witness whereof I have signed and sealed this specification this 1st day of Nov., 1928.

HARRY SKLAR.
